UNITED STATES PATENT OFFICE.

HENRY P. THOMPSON, OF CHICAGO, ILLINOIS.

SPOT LAMP.

Application filed December 17, 1919. Serial No. 345,631.

To all whom it may concern:

Be it known that I, HENRY P. THOMPSON, a citizen of the United States, residing at Chicago, in the county of Cook and State 5 of Illinois, have invented a certain new and useful Improvement in Spot Lamps, of which the following is a full, clear, concise, and exact description, reference being had to the accompanying drawings, forming a 10 part of this specification.

The present invention relates to spot lamps for automobiles, motor boats, etc., and embodies improvements upon the form of spot lamp disclosed in my co-pending application, Serial Number 301,167, filed June 2, 15 1919.

The device disclosed in my co-pending application embodies an automobile spot lamp arranged in combination with a novel form 20 of remote control which is situated in the driver's compartment in convenient position for operation. The particular advantage of this remote control feature lies in the general facility with which the lamp can be 25 operated, and in the fact that the lamp can be operated when the side curtains of the car are down. Furthermore, this control feature particularly adapts the spot lamp to use on limousines and other closed cars by 30 reason of the control thereof being located in the driver's compartment.

The present invention is particularly concerned with the provision of an improved form of locking means for a spot lamp of the above description. This locking means is necessitated by the fact that the spot lamp is subjected to severe vibration and jarring from the motion of the automobile, and it is therefore imperative that 35 means be provided for effectively holding the lamp in its adjusted position. It is the primary object of the present invention to provide such locking means, preferably in the form of a positive lock or detent which 40 is incapable of being jarred loose by the vibration of the machine. A secondary object of the invention is to provide a form of positive lock or detent which can be operated with facility and which will not hinder 45 or encumber the operation of the lamp.

The invention is illustrated in the accompanying drawing, wherein a preferred embodiment thereof is shown.

In the drawing:

Figure 1 is an elevational view of my improved spot lamp mounted upon the windshield of an automobile; 55

Figure 2 is a longitudinal sectional view of the control mechanism; with the central portion thereof broken away; 60

Figure 3 is a transverse sectional view taken on the plane of the line 3—3 of Figure 2; and 65

Figure 4 is an enlarged sectional view taken on the plane of the line 4—4 of Figure 2.

The spot lamp, which is designated 1 in its entirety, is of any preferred conventional type, and is supported on the end of a tubular arm 2 through which extends the operating mechanism for operating the lamp. The tubular arm 2 has a mounting in a suitable clamp 3 which is clamped to the side rail 4 of the wind shield. Supported on the inner end of the tubular arm 2, and in a convenient position for operation by the driver, are two control handles 6 and 7. 70

Referring to Figure 2, the tubular arm 2 consists of a sleeve 8 through which extend an operating sleeve 9 and a central shaft 10. 80 The operating sleeve 9 is arranged to be rotated by the control handle 6, and the operating shaft 10 is arranged to be rotated by the handle 7. On the outer end of the tubular arm 2 is mounted a rotatable head member 12, which has fixed connection with the operating sleeve 9. The outer sleeve 8 is set into a groove 13 recessed into the end of the head 12. Inside the head 12, the shaft 10 carries a bevel gear 14 which meshes with a 85 similar bevel gear 15 on the short transverse shaft 16. The head member 12 is of forked formation, and this stub shaft 16 is journaled in the fork extensions of the head. The shaft 16 is held against outward displacement by the hub of the bevel gear 15 being pinned thereto as at 17. A compression spring 18 bearing against the bevel gear 15 prevents any vibration and rattling due 90 to play of the stub shaft 16. A semi-circu- 95

100

lar cover member 19 encloses the open front of the head 12.

The upper end of the stub shaft 16 is provided with a collar 21, which bears upon the 5 top of the head 12 and is adapted to receive the tubular socket extension 22 of the lamp 1. To permit of the convenient removing and replacing of the spot lamp for use about the car, there is provided a releasable detent 10 pin 23, in the socket extension 22, adapted to have interlocking engagement with the collar 21. The collar 21 is formed with an inverted keyhole slot 24, and one side of the collar is milled off to provide the recess 25. 15 Co-operating with the keyhole slot 24, is a keyhole slot 26 in the socket extension 22. The end of the detent pin 23 is provided with a short radially extending pin 27. It will be apparent that to release the spot 20 lamp, the handle extension 28 is simply rotated to bring the short pin 27 in line with the keyhole slot, and the detent pin 23 is then retracted so as to bring the radial pin 27 into the recess 25. The lamp can then 25 be removed for use about the car. The replacing of the lamp will be obvious from the foregoing.

Referring again to the control handles 6 and 7, it will be noted that the handle 6 consists of a tubular stem formed with a split 30 clamp 30 at its lower end which embraces a collar 31 on the operating sleeve 9. The end of the sleeve 9 is threaded to receive the collar 31, which is screwed up snugly against the outer housing sleeve 8. The collar 31 is provided with a set screw 32 for rigidly clamping the collar to the threaded end of the sleeve 9. The clamp portion 30 is rigidly clamped on the collar 31 by a screw 33 which 35 threads through the two depending ears of the clamp. The clamp mounting of the handle 6 on the collar 31 is advantageous in that it permits of angular adjusting of the handle relative to the plane of the lamp 1, but it 40 will be apparent that the handle 6 may be otherwise mounted on the sleeve 9.

The stem of the handle 6 contains a small plunger 34, which projects up through the enlarged end of the handle in the form of 45 a depressible button 35. The enlarged end of the stem is counterbored as indicated at 36, to receive the enlarged button end of the plunger. Between the button 35 and the bottom of the counterbore is confined a small 50 compression spring 37, which normally tends to raise the plunger 34. The lower end of the plunger 34 has pivotal connection with a detent pawl or dog 38, which is pivoted on a pivot pin 39 mounted transversely in the body of the stem. The dog 40 projects out through a slot 41 in the stem, and is adapted to engage between the teeth of a toothed ring 42 provided on the end of the stationary outer sleeve 8.

65 Threading onto the end of the operating

sleeve 9 is a second collar 43, which is provided with a reduced extension adapted to engage in a recess formed in the face of the collar 31, as indicated at 44. A portion of the collar 43 is formed co-extensive with the 70 collar 31 and this portion is embraced by the clamp 30, so that the clamp rigidly binds the two collars together. The outer portion of the collar 43 is formed with an enlarged flange having a laterally projecting pin or stud 45 formed integral therewith. The stud 45 is adapted to engage in one of a series of holes 46 formed in the hub 47 of the handle 7 (Figure 3). The handle 7 merely consists of a wheel or disc, the periphery of which is grooved to facilitate gripping by the fingers, and this wheel is mounted for shiftable movement on the squared extension 48, formed integral with the shaft 10. A bushing 49 is mounted in 80 the circular bore of the hub, this bushing having a squared hole for engaging over the squared end 48. The hub of the hand wheel 7 is counterbored, as indicated at 51, to receive a compression spring 52 which is confined therein by a screw 53 tapping into the end of the shaft extension 48.

In the operation of the lamp, horizontal adjustment is given the lamp by retracting the handle 7 to the dotted line position 95 (Figure 1,) to clear the pockets 46 of the stud 45, and then rotating the handle in either direction to swing the lamp to the right or the left as desired. Upon release of the handle 7 the same is automatically 100 shifted back into locking engagement, with the stud 45 projecting into one of the pockets 46. To obtain a vertical adjustment of the spot lamp, the handle 6 is actuated by depressing the button 35 and swinging the 105 handle to the side or down, as indicated in dotted line position. This rotates the entire head 12 so as to swing the lamp in a vertical plane, and by the co-operating adjustment to the handle 7 it will be seen that any desired angular adjustment can be given the lamp 1. It will be apparent that when only the handle 6 is actuated, the handle 7 will move concurrently therewith by reason of its being locked thereto through the collar 110 43. When the handle 6 has been moved to its desired position and the button 35 is released, the dog 38 automatically locks in the teeth 42 and holds the lamp against shaking down or vibrating out of position. The handle 6, being rigidly locked to the stationary outer tube 8, and the handle 7 being locked to the handle 6 through the collars 43 and 31, it will be seen that this latter handle is consequently also rigidly 115 locked against vibration and movement of the lamp.

It will be observed that in the case of each control, the positive lock thereof is releasable by a simple and convenient motion 120

which does not encumber the operation of the lamp.

It is to be understood, of course, that the foregoing details of the particular construction and arrangement may be varied widely within the scope of the invention. I do not, therefore, intend limiting the invention, except as defined within the spirit and scope of the appended claims.

10 I claim:

1. In combination, a spot lamp, a pair of concentric members for operating said lamp, a relatively stationary locking member comprising a serrated ring concentric with the outer operating member, a control handle carried by said outer operating member, a pawl carried by said control handle, spring means normally projecting said pawl into said serrated ring, said control handle being released for lamp actuating motion by the pivotal tripping of said pawl, a control handle on the inner operating member, and means for locking said second control handle to said outer operating member.

25 2. In combination, a spot lamp, a pair of concentric members for operating said lamp, a housing sleeve over said outer operating member, a serrated ring carried by said housing sleeve, a control handle mounted on said outer operating member, a second control handle on the inner operating member in immediate proximity to said first control handle, a pawl pivotally mounted on said first control handle, spring means normally projecting said pawl into said serrated ring, said pawl comprising operating means adapted to be depressed inwardly towards the axis of said operating members, and independent locking means for said second control handle, said latter locking means being released by shifting motion of said handle.

30 3. In combination, a lamp for automobiles and the like, a pair of concentric operating members for operating said lamp, a relatively stationary locking member comprising a serrated ring, a control handle on the outer operating member, a pawl pivotally mounted on said control handle, spring means normally projecting said pawl into said serrated ring, said pawl being released by the depression of the same inwardly toward the axis of said operating members, a second control handle on the inner operating member, and locking means for said latter handle intermediate said handles, said locking means comprising a locking member having a plurality of locking recesses therein, and a cooperating member having a locking projection adapted to engage in said recesses, one of said locking members being carried by said second control handle and being released by shifting motion of said handle.

35 4. In combination, a spot lamp, a pair of

concentric operating members for said lamp, a relatively stationary locking member comprising a ring having a plurality of locking projections thereon, a control handle on the outer operating member, a pawl moving with said control handle, spring means normally projecting said pawl into the locking projections of said ring, a second control handle on the inner operating member, locking means for said latter handle intermediate said handles, said locking means comprising a first locking member having a plurality of locking recesses therein, and a second locking member having a projection adapted to engage in said recesses, one of said locking members being carried by said second control handle, said locking members being released by endwise motion of said handle, and spring means for yieldably holding said locking members engaged.

5. In combination, a supporting member, a rotatable sleeve carried by said supporting member, an operating member within said sleeve, a head member at the outer end of said sleeve and adapted for rotation thereby, a stem in said head member, a spot lamp carried on said stem, gearing connecting said stem with the operating member within said sleeve, independent control handles at the inner ends of said sleeve and said operating member, a relatively stationary locking member, a latch carried by the control handle on said sleeve for engaging with said stationary locking member, and manually releasable positive locking means associated with the other of said control handles for locking the same to said sleeve.

6. In combination, a rotatable sleeve, a shaft within said sleeve, a head member carried by the outer end of said sleeve, a spot lamp rotatably supported on said head member, means operatively connecting said shaft with said spot lamp for transmitting rotary motion to the latter, a control handle at the inner end of said sleeve, means for positively locking said control handle to a relatively stationary point, a second control handle at the inner end of said shaft, and positive locking means for locking said second control handle to said sleeve, said latter locking means being releasable by translational motion of said second operating handle.

7. In combination, a rotatable sleeve, a shaft therein, a head member carried on the outer end of said sleeve, a spot lamp rotatably supported on said head member, means connecting said shaft with said spot lamp for rotating the latter relative to said head member, a first control handle mounted on the inner end of said sleeve, a stationary locking member, a latch carried by said control handle for locking the latter to said

locking member, a second control handle mounted on the inner end of said shaft, means for locking said control handles together, and a spring normally retaining 5 said locking means engaged, said locking means being disengaged by rectilinear motion of said second operating handle.

8. In combination, a spot lamp for automobiles and the like, an outer housing sleeve, 10 operating mechanism extending through said sleeve and having operative connection with said lamp for angularly adjusting the same, a control lever at one end of said sleeve and having connection with said operating 15 mechanism a notched ring on said sleeve, a locking detent carried by said lever and normally engaging in said notched ring, a depressible button in said lever for releasing said locking detent, a collar having connection 20 with said control lever, a control knob having operative connection with said operating mechanism, and pin and socket locking means between said collar and said control knob, said locking means being releasable 25 by axial movement of said control knob.

9. In combination, a fixed support, two concentric members journaled in said support, a handle for actuating the inner concentric member, means normally yieldably actuated to lock said outer concentric member to said support and to said inner member, manually released means for releasing said outer member from said support to move with said inner member, or from said inner member to permit movement of said inner, but not said outer member, and a spot light connected to said members for rotation about one axis by actuation of said 40 outer member, and about another axis at an angle to said first axis by actuation of said inner member with respect to the outer.

10. In combination, a spot lamp for automobiles and the like, control means for angularly adjusting said lamp, operating means connecting said control means with said lamp, said operating means comprising a rotatable head member, a stub shaft projecting from said head member and having 45 an interlocking slot therein, a socket extension projecting from said lamp and adapted to be mounted on said stub shaft, and a locking pin in said socket extension co-operating with the interlocking slot in 50 said stub shaft for releasably locking said socket extension and stub shaft together.

11. In combination, a supporting member, a pair of concentric operating members extending through said supporting member, 60 a head carried at the end of the outer operating member and rotatable therewith, a stem journaled in said head at an angle to the axis of said outer operating member, means operatively connecting the inner operating member with said stem for trans-

mitting rotary motion thereto, a spot lamp carried by said stem, said spot lamp being detachable for use as a trouble lamp, and an electrical conductor extending to said spot lamp, said conductor being external of 70 said supporting member and said operating members whereby the removal of said spot lamp is permitted.

12. In combination, a tubular supporting member, a pair of concentric operating members extending through said supporting member, control means at one end of said operating members for actuating the same, a head carried by the outer operating member and rotatable therewith, a stem journaled in said head, means operatively connecting said stem with the inner operating member, a spot lamp carried by said stem, and an electric conductor for said lamp extending thereto externally of said supporting member, said operating members, 80 said rotatable head and said stem.

13. In combination, a stationary locking member, two concentric members rotatable relative to said locking member, an operating handle mounted on one of said concentric members, a first locking means normally yieldably actuated to lock one of said concentric members directly to said stationary locking member, a second locking means operative to lock the other of said concentric members to said first concentric member, each of said locking means being manually releasable for permitting rotation of its corresponding concentric member, a housing supported at the outer end of one of said concentric members and connected thereto for rotation thereby about the axis of said concentric members, a stem pivotally mounted in said housing, a spot lamp 105 mounted on said stem, a gear concentric with the axis of said concentric members and connected to the other of said concentric members, and a second gear connected to said stem and meshing with said first gear.

14. In combination, a spot lamp, and operating mechanism therefor comprising a central shaft, a sleeve surrounding said shaft, a stationary tubular member supporting said sleeve, a control member on said sleeve, a second control member on said shaft, a stationary locking member comprising a plurality of locking recesses concentric with said sleeve, a manually releasable pawl moving with said first control member 115 and adapted to engage in said recesses for positively locking said control member, and independent detent means for connecting said second control member to said sleeve.

15. In combination, a spot lamp, and operating mechanism therefor comprising a central operating member, a sleeve surrounding said central operating member, a stationary tubular member surrounding said sleeve, locking means associated with said 125 130

stationary member and having a plurality of locking recesses, a control member on said sleeve, a pawl moving with said control member and adapted for engagement 5 with said locking recesses for positively locking said control member, a second control member on said central operating member,

and locking means for locking said control members to each other.

In witness whereof I hereunto subscribe 10 my name this 12th day of December, A. D. 1919.

HENRY P. THOMPSON.
